(57) **CLAIM**

The ornamental design for an electrode for use on a living subject with removal protective electrode carrier, as shown and described.

DESCRIPTION

FIG. 1 is a top perspective view of an electrode for use on a living subject showing our new design, with the protective carrier removed;

FIG. 2 is a top plan view of the electrode of FIG. 1;

FIG. 3 is a bottom plan view thereof;

FIG. 4 is a first side view thereof;

FIG. 5 is a second side view thereof;

FIG. 6 is a front view thereof;

FIG. 7 is a rear view thereof; and,

FIG. 8 is a top perspective view of the electrode of FIG. 1 mounted on the protective electrode carrier.
